UNITED STATES PATENT OFFICE.

HOMER M. SACKETT, OF DENVER, COLORADO.

FRICITION-GRIP.

SPECIFICATION forming part of Letters Patent No. 655,519, dated August 7, 1900.

Application filed July 30, 1897. Renewed June 25, 1900. Serial No. 21,572. (No model.)

To all whom it may concern:

Be it known that I, HOMER M. SACKETT, of Denver, in the county of Arapahoe, and in the State of Colorado, have invented certain new and useful Improvements in Friction-Grips; and I do hereby declare that the following is a full, clear, and exact description thereof, reference being had to the accompanying drawings, in which—

10 Figure 1 is a top plan view of my grip; Fig. 2, a bottom plan view thereof with the covering-plate removed; Fig. 3, a view partly in section and partly in end elevation, and Fig. 4 a view partly in section and partly in side elevation.

Letters of like name and kind refer to like parts in each of the figures.

The object of my invention is to provide a simple, safe, easily-operated, and efficient 20 grip for use in attaching cars, buckets, skips, or other objects to be moved to a moving or running rope or cable; and to this end said invention consists in the grip having the features of construction substantially as hereinafter specified.

In the carrying of my invention into practice I employ a frame A, having a cylindrical opening in which is fitted a hollow casting B, whose lower end is open and whose upper 30 end is closed and provided with a flange b, that overhangs and rests upon the top of the frame A. The lower end is removably closed by a cap or cover C, that has an annular flange encircling said end and fastened there- 35 to by bolts D and D. The upper edge of said flange abuts against the lower end of the frame A, and as the casting-flange b engages the upper end of the frame A said casting is firmly held from longitudinal movement or 40 movement in an axial direction, although free to turn or revolve within the frame-opening.

The parts A, B, and C are preferably cast-steel.

To the vertical face of a boss or block E, 45 formed on the top of the part B, is fastened by bolts or otherwise a plate F, having a groove in its side to engage one side of the rope or cable, said plate being one of the gripping-jaws of the device and being a fixed 50 one. To adjust said jaw to work on ropes or cables of different size, shimming-plates of copper or other material are placed between

the same and the boss or block E, by the addition or removal of which the position of said jaw may be changed.

A movable jaw G is attached to the upper end of a lever H, that is pivoted upon a pin I, between ears K and K, cast on the top of the part B, the lever being carried beneath its pivot into said part and at its lower end 60 pivoted to one end of a link L by a pin M, the other end of which link is pivoted by a pin N to two parallel links O and O, which are pivoted on a pin P, passing through a boss or lug b', projecting inward from the 65 side of the part B. The links L and O constitute a compound lever or toggle. Connected to the pin N, that pivots the links of the toggle together, are the lower ends of two parallel links Q and Q, to and between whose 70 upper ends is pivoted on a pin R the lower end of an upwardly-extending lever S, that is pivoted on a pin T, between ears or lugs cast on the top of the part B. By means of said lever S the grip is opened and closed.

When the movable jaw is in gripping position, the centers of the pivots M, N, and P are in a straight line, and the centers of the pivots N, R, and T are also in a straight line, with the upper parts of the links Q and Q engaging the lower end of the jaw-lever H, so as to limit the swing of the operating-lever S in the direction for closing the jaw when said centers N, R, and T are in line. It will be seen that by the placing in line with each 85 other of the centers, as described, the movable jaw is thereby locked or held in gripping position without the intervention of springs, catches, or other lock devices.

Any tendency of the jaw-lever to open will 90 be opposed by the alining of the three centers M, N, and P, and any tendency of the toggle to move will be opposed by the alining of the three centers N, R, and T.

To release the grip, the lever S is moved 95 down to the position shown in Fig. 3. In such movement it raises the links Q and Q and lifts the connected ends of the toggle, swinging the end of the link L that is connected to the jaw-lever H toward the fixed pivot of 100 the links O and O until said link L strikes the pivot-lug b' and the movement is arrested, with the various parts in the position shown by dotted lines, Fig. 3. The weight of the por-

tion of the lever S above its pivot is sufficient to counterbalance the weight of the other part of it and the parts connected therewith, so that there is no tendency of the parts, due 5 to their weight when in the position shown in dotted lines, Fig. 3, to move and accidentally close the movable jaw. Thus, as when the grip is closed, no locking devices of any description are required to hold the grip in 10 an open position, and in each position the parts are in readiness to instantly respond to the movement of the operating-lever S.

It will be noted that the movement of parts to each position is limited by utilizing the 15 links themselves as the stopping means.

Although the casting or part B is free to turn in the opening in the frame A to enable the grip to adapt its position to the angle or direction in which the rope or cable may be 20 running, yet when the rope or cable is released there will be no tendency of the part B to thus turn, because the location of the parts and the disposition of the metal are such as to place the center of gravity below the 25 center of the device.

In closing the movable jaw the movement of the jaw, by reason of the peculiar arrangement of links connecting the operating-lever S and the jaw-lever H, is at first comparatively rapid, becoming gradually slower, but with an increase of power, the greatest power being exerted at the time of gripping or taking hold of the rope or cable.

The compact arrangement of the levers, 35 which I have secured, enables such complete housing thereof within the casting B and the cover-plate C that they are thoroughly protected from dirt and weather.

It is of course to be understood that I do 40 not limit the use of my invention to any particular location of the driving rope or cable or with any particular object or contrivance to be moved by such rope or cable, and of course the operating-lever may be actuated 45 by hand or automatically.

Having thus described my invention, what I claim is—

1. In a grip, the combination of a pivoted jaw, a toggle pivotally connected therewith at one end, and at the other end to a relatively-fixed point, a link connected to the toggle between its ends, and a lever connected to said link, that moves the toggle through the link to bring the toggle ends toward each other to open the jaw, and to move said ends from each other to close said jaw, substantially as and for the purpose described. 50

2. In a grip, the combination of a jaw to be moved, a toggle connected therewith, a link connected with the toggle, and a lever connected with said link, the pivotal centers of the lever and the link, being adapted to be placed in a straight, or substantially straight, line to form a lock, substantially as and for the purpose described. 60

3. In a grip, the combination of jaw-actuating mechanism, and a chambered part, within which such mechanism is mounted, inclosing and protecting the same, having one end permanently closed and carrying a fixed jaw, and 70 the other end closed by a removable cover, substantially as and for the purpose described.

4. In a grip, the combination of the jaws, the jaw-actuating mechanism, and a revolvable support therefor, substantially as and for the purpose described. 75

5. In a grip, the combination of a fixed jaw, a movable jaw, means for actuating the latter, a cylindrical casting or part, on which all 80 of said parts are mounted, and a frame in which said casting is revolvably mounted, substantially as and for the purpose specified.

In testimony that I claim the foregoing I have hereunto set my hand this 19th day of 85 July, 1897.

HOMER M. SACKETT.
